UNITED STATES PATENT OFFICE.

MAURICE C. RYPINSKI, OF SCHENECTADY, NEW YORK, ASSIGNOR TO
GENERAL ELECTRIC COMPANY, A CORPORATION OF NEW YORK.

ELECTRIC RAILWAY.

No. 803,365.

Specification of Letters Patent.

Patented Oct. 31, 1905.

Application filed March 31, 1902. Serial No. 100,671.

To all whom it may concern:

Be it known that I, MAURICE C. RYPINSKI, a citizen of the United States, residing at Schenectady, county of Schenectady, State of New York, have invented certain new and useful Improvements in Electric Railways, of which the following is a specification.

My invention relates to electric railways in which the energy is obtained from a third rail or conductor located either between or just outside the tracks and which is formed of sections normally disconnected from the source of supply, but rendered active by the approaching car or train.

My invention consists of electromagnetic switches located in the connections between the sections of the third rail or conductor and the feeder and means for energizing and deenergizing said electromagnetic switches, which means comprises auxiliary switches located adjacent the track-rail and operated by the passing car, said auxiliary switches being adapted to connect the ends of the coils of said electromagnetic switches either to ground or to the feeder.

In the accompanying drawings, Figure 1 is a diagrammatic representation of my sectional third-rail system, showing the manner in which the sectional third rail is rendered active by a car passing over the line. Fig. 2 represents diagrammatically the same system, showing how the sectional third rail is rendered active by a car following the car shown in Fig. 1 in the same direction. Fig. 3 is a sectional elevation of one form of mechanically-operated switch. Fig. 4 is a section on the line 4 4 of Fig. 3, and Fig. 5 is a section on the line 5 5 of Fig. 3.

Referring now to Figs. 1 and 2, F represents the feeder, R', R², and R³ sections of third rail or conductor, which are made approximately the length of the car operating thereon, and S', S², and S³ the electromagnetic switches for connecting the sectional conductor to the feeder. C represents a car carrying the motor M, and R the track-rails on which said car runs. In the system illustrated the track-rails are used as the return. Switches s', s², and s³, mechanically operated by a projection carried by the car, are located along the track, as shown, and serve to successively connect the operating-coils a', a², and a³ of the electromagnetic switches

S', S², and S³ in circuit with the source of supply. The coils a', a², and a³ of the switches S', S², and S³ are permanently connected together in series through the conductor 4 4', and the connections between adjacent coils are also connected, respectively, to the fixed contacts b of the switches s', s², and s³ through the conductors 2 2', &c., as shown. The fixed contacts d of the switches s', s², and s³ are connected to ground or the rail-return R through the conductors 3 3', &c., while the contacts c are connected directly to the feeder F through the conductor 1 1', &c. The movable contact e of each of the switches s', s², and s³ is adapted to connect the contact b with either of the contacts c or d, as desired.

In Figs. 3, 4, and 5 I have shown one form of the switch s'. The fixed spring-contacts b, c, and d of the switch are shown as mounted within the moisture-proof casing c'. The contact b is shown in Fig. 5 as divided into two parts electrically connected, as it would be much easier to manufacture in this form. Such a construction allows the movable contact-bar e to move freely between the fixed contacts. The contact-bar e is carried by the shaft p, which passes through the diaphragm d' in the casing c' and is rotatably mounted therein. Fixed on the upper end of the shaft p is the star-shaped impact-receiving wheel k, which is maintained in the position into which it may be forced by the projection h, carried by the car, by means of the spring n, which is fixed to the protecting-hood c², which forms the upper part of the casing c'. The spring n coacts with the arms of the star-shaped wheel successively and prevents said wheel from moving more than one arm or ninety degrees at one time. R represents the track-rail; w, a wheel of the car; R', the sectional third rail, and T the trolley or collector-shoe co-operating therewith. The switch-contacts can be readily removed from the casing c' through the bottom of the casing c' after removing the base-plate t.

The operation of the system will now be described. The car C in Fig. 1 is supposed to be moving in the direction of the arrow and the switches s' and s² on the left of the figure to have been thrown by the passing car into the position shown. It will be seen

that both sides of the coil a' have been connected to the rail-return, thereby deenergizing the electromagnetic switch which connects the rail R' with the feeder. The car in the position shown is taking current through the switch S^2 , the coil a^2 of which has been energized by a current through the conductor 1' from the feeder F, through contact c of switch s^3 , movable contact e, contact b, conductors 2' and 4', coil a^2 , conductors 4 and 2 to contact b of switch s^2 , movable contact e, contact d, conductor 3 to rail-return R. As the car moves forward the switch s^3 is thrown into the position shown in Fig. 2, both sides of the coil a^2 are grounded, the switch S^2 opens by gravity, though it may be assisted in opening by means of a spring or the like, and the rail R^2 becomes deenergized, while the rail R^3 becomes energized, as above described. The car shown in Fig. 2 has thrown the switches s' and s^2 from the position shown in Fig. 1 to the position shown in Fig. 2, thereby connecting both ends of the coil a' to the feeder, depriving the coil a' of current and allowing the switch S' to open. The rail R^2 is energized by its connection to the feeder through the switch S^2 , the coil a^2 of which receives current from the feeder through the following circuit: conductor 1, contact c of switch s^2 , movable contact e, contact b, conductors 2 and 4, coil a^2 , conductors 4' and 2', contact b, movable contact e, and contact d of the switch s^3 , the conductor 3' to the rail-return R. As the car moves forward the switch s^3 is thrown into the position shown in Fig. 1, both sides of the coil a^2 being connected to the feeder F, deenergizing the switch S^2 and simultaneously energizing the switch S^3 , as above described.

While I have shown my invention as applied to a sectional third-rail system, I do not limit myself thereto, since my invention is equally applicable to a surface or button-contact system in which a long contact-shoe is carried by the car.

My invention is also applicable as a blocking system either on overhead trolley-roads or third-rail roads on which the third rail or trolley is divided into long sections, on each of which but one car or train is to be allowed at one time. Should a second train or car enter the block or section, both cars or trains would be deprived of current, as will be readily understood, for instance, by reference to Fig. 1. If a second car should enter the section occupied by the car C, the switch s^2 would be thrown so as to connect the end of the coil a^2 controlled by said switch to the feeder, and since the other end of said coil is connected to feeder through the switch s^3 no current would flow through the coil a^2 . After coming to a stop neither car nor train can move until one of the switches s' , s^2 , &c., controlling that block has been rotated ninety degrees by hand.

What I claim as new, and desire to secure by Letters Patent of the United States, is—

1. In an electric railway, the combination of a sectional working conductor, a feeder, connections between said feeder and the sections of said working conductor, switches in said connections, actuating-coils for said switches, and separate switches operated from one working position to another by a passing car for controlling the connections of 75 said actuating-coils.

2. In an electric railway, the combination of a sectional conductor, a feeder, connections between said feeder and the sections of said conductor, switches in said connections, 80 actuating-coils for said switches, permanent connections joining the terminals of said coils, and separate switches operated by a passing car for connecting said permanent connections to the feeder or to the return, as 85 desired.

3. In an electric railway the combination of a sectional working conductor, a feeder, connections between the sections of said conductor and said feeder, switches in said connections, actuating-coils for said switches, controlling-switches for said actuating-coils having two working positions, and means for mechanically operating said latter switches from one working position to another by a 95 passing car.

4. In an electric railway, the combination of a sectional working conductor, a feeder, connections between the sections of said conductor and said feeder, switches in said connections, actuating-coils for said switches, permanent connections joining the terminals of said coils, and means connecting said permanent connections either to the feeder or to the return, as desired. 105

5. In an electric railway, the combination of a sectional conductor, a feeder, connections between said feeder and the sections of said conductor, switches in said connections, actuating-coils for said switches, permanent 110 connections joining the terminals of said coils, and switches adapted to be operated mechanically by a passing car for connecting said permanent connections either to the feeder or to the return as the car progresses. 115

6. In an electric railway, the combination of a feeder, a return-circuit, a plurality of electromagnetic switches, and means for connecting the terminals of the actuating-coils of said switches either to the feeder or to said 120 return-circuit as desired.

7. In an electric railway, the combination of a feeder, a return-circuit, a plurality of switches, actuating-coils for said switches, permanent connections between the terminals of said coils, and auxiliary switches adapted to be operated by a passing car for connecting said permanent connections alternately to the feeder and to the return-circuit. 125 130

8. In an electric railway, the combination of a feeder, a section of working conductor, a connection between said feeder and said section, an electromagnetic switch in said connection, and switches adapted to connect the ends of the coil of said electromagnetic switch alternately to said feeder and the return.
9. In an electric railway, the combination of a feeder, a section of working conductor, a connection between said feeder and said section, an electromagnetic switch in said connection, a switch adapted to connect one end of the coil of said electromagnetic switch alternately to the feeder and the return, and an independent switch adapted to connect the other end of said coil alternately to said feeder and the return.
10. In an electric railway, the combination of a feeder, a section of working conductor, a connection between said feeder and said section, an electromagnetic switch in said connection, a switch operated by a passing car and adapted to connect one end of the coil of said electromagnetic switch alternately to said feeder and the return, and an independent switch operated by the car and adapted to connect the other end of said coil alternately to the feeder and the return.
11. In an electric railway, the combination of a sectional conductor, a feeder, connections between said feeder and the sections of said conductor, electromagnetic switches in said connections, and switches operated by the passing car for connecting the terminals of the actuating-coils of said electromagnetic switches to the feeder or to the return as desired.
12. In an electric railway, the combination of a feeder, a return-circuit, an electromagnetic switch, and means for connecting both ends of the actuating-coil of said switch to the feeder or to the return for the purpose of deenergizing said switch and for connecting one end of said coil to the feeder and the other end to the return for the purpose of energizing said switch.
13. In an electric railway, the combination of a feeder, a return-circuit, a plurality of electromagnetic switches, means for connecting both ends of the actuating-coil of each of said switches either to the feeder or to the return for the purpose of deenergizing said switches and for connecting either end of said coil to the feeder and the other end to the return for the purpose of energizing said switches.
14. In an electric railway, a sectional working conductor, a feeder and a return-circuit, electromagnetic switches for connecting the sections of the working conductor to the

feeder, and means for connecting one end of the actuating-coil of each of said switches to the feeder and the other end of said coil to the return for the purpose of energizing the section of working conductor controlled by 65 said switch and for connecting both ends of the said coil either to the feeder or to the return for the purpose of deenergizing said section of working conductor.

15. In an electric railway, a sectional working conductor, a feeder, a return-circuit, electromagnetic switches for connecting the sections of the working conductor to the feeder, and means operated by a passing car for connecting one end of the actuating-coil of each 70 of said switches to the feeder and the other end of said coil to the return to cause said electromagnetic switches to close, and for connecting both ends of the said coil either to the feeder or to the return to allow said 75 switches to open.

16. In an electric railway, the combination of a feeder, a section of working conductor, a connection between said feeder and said section, an electromagnetic switch in said connection, a switch adapted to connect one end of the actuating-coil of said electromagnetic switch alternately to the feeder and to the return, and an independent switch adapted to connect the other end of said coil alternately to 80 said feeder and the return, both ends of said coil being connected either to the feeder or to the return when said coil is deenergized and one end of said coil being connected to the feeder and the other end to the return 85 when said coil is energized.

17. In an electric railway, the combination of a feeder, a section of working conductor, a connection between said feeder and said section, an electromagnetic switch in said connection, a switch operated by a passing car to connect one end of the coil of said electromagnetic switch alternately to the said feeder and return, and an independent switch operated by the car to connect the other end of 100 said coil alternately to the feeder and the return, one end of said coil being connected to the feeder and the other end connected to the return when the section of working conductor is energized and both ends of said coil being connected either to the feeder or to the return when said section of working conductor is deenergized.

In witness whereof I have hereunto set my hand this 28th day of March, 1902.

MAURICE C. RYPINSKI.
